UNITED STATES PATENT OFFICE.

FRANK A. YOUNG, OF NEW YORK, N. Y., ASSIGNOR TO UNDERWOOD TYPEWRITER COMPANY, OF NEW YORK, N. Y., A CORPORATION OF NEW JERSEY.

TYPE-WRITING MACHINE.

1,139,946.

Specification of Letters Patent. Patented May 18, 1915.

Application filed March 5, 1910. Serial No. 547,416.

To all whom it may concern:

Be it known that I, FRANK A. YOUNG, a citizen of the United States, residing in New York, in the county of New York and State 5 of New York, have invented certain new and useful Improvements in Type-Writing Machines, of which the following is a specification.

This invention relates to the tabulators 10 commonly used in conjunction with the carriages of typewriting machines, the object of the invention being to provide improved means for locking the stops to the bar on which they are mounted and along which 15 they are adjustable.

The improvement is illustrated in connection with the tabulator shown in my Patent 961,280, dated June 14, 1910.

According to the present invention, the 20 column stops consist of forks which bestride a column stop rack, the forks being adjustably seated between teeth formed on opposite sides of the rack. I extend the forks down below or beyond the rack, and contrive, by means of these extended portions, to lock the stops against upward displacement or withdrawal from the rack. This locking is effected by a locking bar which 25 extends along the rack bar between the forks 30 of the stops. The locking bar is rotatable, and when in one position, it permits the ready insertion and withdrawal of the stops; but when rotated to another position it turns 35 into notches provided in said extensions of the forks, and thereby prevents them from lifting. Other objects and advantages will hereinafter appear.

In the accompanying drawings, Figure 1 is a perspective view, from the rear and underneath of a tabulator. Fig. 2 is a rear view of the same. Figs. 3 and 4 are cross-sectional views illustrative of the operation of parts.

The reference numeral 2 marks a bar 45 which is rigidly connected to the frame of the typewriting machine (not shown) by the brackets 3, the bar 2 and the brackets being secured to each other, as by screws 4. This bar 2 is adapted to hold the tabulator stops 5 by means of the rack teeth at the front and rear sides of said bar and the parallel legs 6, 7 forming part of said stop, which

straddle the bar 2 between teeth thereof, whereby said stop is firmly held against motion endwise of said bar 2 but may be placed 55 thereon and be removed therefrom by motion in one direction transverse to said bar.

A rocking bar is adapted to move into and out of position for locking such stops against such transverse motion. Such rocking bar 60 may co-act with the stops in any suitable manner, as with a corner or shoulder thereon, or with a notch on an edge of the stop which is substantially parallel with the direction of motion of the stop in putting it on 65 the bar 2. In the arrangement shown in the drawing, a rocking bar is shown at 8; it is journaled in lugs or ears 9 on the under side of the fixed bar 2. This bar 8 is of a transverse dimension a in one direction 70 greater than its transverse dimension b in another direction, and such greater dimension is greater than the width of the slot 10 between the legs 6, 7 of the stops at the open end of such slot. The slot 10 is widened at 75 a point between its open and closed ends to allow the rod 8 to be turned so as to bring the wider part a across or transverse to the length of slot 10 and thereby prevent the removal of the stop from the bar 2, as indicated in Fig. 3. By turning the rod 8 to the position thereof shown in Fig. 4, the stop is released for removal from the bar 2, as the dimension b is less than the width of the slot 10. In the instance illustrated, the 80 widened part of the slot 10 consists in a notch 11 in one of the edges of the metal leg 7, thus forming a sort of shoulder at one side of slot 10. By using a round rod 8 which is flattened on one side, as at 12, a 85 simple, durable and convenient lock is provided for retaining the stops 5 in place on the bar 2.

A knob 13 is fast on the rod 8 at one end thereof, whereby it may be operated by the 95 thumb and fingers. The sleeve 14 of the knob 13 abuts against the end of the bar 2 to prevent motion of the rod 8 endwise in one direction while motion of said rod 8 in the reverse direction is prevented by a 100 pin 15 in said rod, and by a lug 9.

It will be observed that one rod or bar 8 co-acts with all the stops 5 whatever may be their position along the bar 2, and that it

locks and unlocks all of them simultaneously.

The friction of sleeve 14 and pin 15 against bar 2 and bearing 9 may be utilized 5 to retain bar 8 in any position to which it is rotated and a mark 16 may be used to indicate whether it is in position for locking the stops.

The dog 17 co-acts with the stops 5, as 10 in said prior patent to arrest the carriage at predetermined points in tabulating.

Having thus described my invention, I claim:

1. In a tabulator, the stop-carrying rack-bar, combined with a stop slotted to straddle 15 said bar between teeth thereof, the slot of said stop being widened at a point between the open and the closed ends thereof, and a journaled stop-lock of a width or thickness 20 in one direction greater than the width of the open end of said stop-slot and adapted to engage in said widened part of said slot to lock said stop in place.

2. In a tabulator, the stop-carrying rack-bar, combined with a series of stops, each 25 slotted to straddle said bar between teeth thereof, the slot of said stop being widened at a point between the open end of said slot and said rack-bar, and a journaled stop-lock 30 common to said stops and of a thickness in one direction greater than the width of the open ends of the stop-slots and adapted to engage in said widened parts of said slots to lock said stops in place.

3. In a tabulator, the stop-carrying rack-bar, combined with a stop-lock slotted to 35 straddle said rack-bar between teeth thereof, the slot in said stop being widened at a point between the open and the closed ends thereof, and a rod wider in one direction than the 40 open end of said slot and journaled parallel to said rack-bar to rotate about its own axis and engage with said widened part of said slot in any position of said stop along said 45 bar.

4. In a tabulator, the stop-carrying rack-bar, and a stop slotted to straddle said bar at any point therealong and provided with a 50 notch in an edge thereof, combined with a rotary rod pivoted at its ends to revolve clear of said bar and by its rotation to enter and leave said notch to lock and unlock said stop.

5. In a tabulator, the stop-carrying rack-bar and a stop slotted to straddle said bar at any point therealong and having the slot thereof widened at a point between the open and closed ends thereof, combined with a rotary rod pivoted at its ends to revolve clear 60 of said bar and by its rotation to engage with and be disengaged from said widened portion of said slot to lock and to release said stop.

6. In a tabulator, the combination with a

toothed rack bar, of a stop having legs straddling said bar, a portion of one of said legs extending clear of the teeth of said rack bar and being notched on the inner side of said extension, and a segmental bar journaled adjacent to said rack bar and adapted, when rotated, to engage its arcuate portion within said notch to lock said stop.

7. In a tabulator, the combination with a toothed rack bar, of a stop having legs straddling said bar, one of said legs having a notch, and a rotatable lop-sided locking bar extending along said rack bar and arranged to be rotated to engage said notch outside of said rack.

8. In a typewriting machine, the combination of a traveling carriage and a rack bar thereon, of a stop formed with a notch therein, and a member pivoted on the carriage clear of said rack bar and adapted to be turned on a horizontal axis into and out of engagement with said notch, said pivoted member lying between the legs of said stop.

9. In a typewriting machine, the combination with a stop, of a bar supporting said stop, notched legs on said stop extending across said bar and beyond it so that there is a space between said legs, and a locking member journaled on and below the bar and extending through said space adapted to be rotated to engage the notches on the legs.

10. In a typewriting machine, the combination with a bar adapted to support stops thereon, of a locking member rotatable in journals on said bar to lock the stops on the bar, a round head on said member, and a mark on said head to show if said locking member is in effective position.

11. In a typewriting machine, the combination with a holding member and a stop having a body, of a leg on said stop by which it engages the holding member, a second shorter leg on said stop also to engage said member, said second leg having a notch therein, and rotary locking means to enter the notch, said locking means extending from end to end of the rack bar and rotatable in the plane thereof.

12. In a typewriting machine, the combination of a supporting bar, notched stops adjustable thereon and bodily removable therefrom in a direction perpendicular to the bar, and a locking member extending along and below the bar on the side thereof opposite the body portions of the stops and adapted to be turned on its axis to engage the notches of the stops.

13. In a typewriting machine, the combination with a stop bar, stops having locking features thereon bodily movable in a direction perpendicular to the bar, and a lop-sided locking member located outside the bar and extending longitudinally thereof, and movable laterally into and out of posi-

tion to lock the stops against said movement.

14. In a typewriting machine, the combination with a rack bar, stops having locking features thereon bodily movable in a direction perpendicular to the bar, of a locking rod outside the bar and extending along one

face thereof, and rotatable into and out of position to lock the stops against said movement.
